COMBINED ESCUTCHEON PLATE AND HINGED COVER FOR A TABLE TOP RECESSED SWITCH DEVICE

Marshall F. Thompson, 3112 W. Marshall St.,
Richmond, Va. 23230

Filed Dec. 16, 1968, Ser. No. 14,996

Term of patent 14 years

Int. Cl. D8—03

U.S. Cl. D8—184

FIG. 2

FIG. 3

FIG. 4

FIG. 5

FIG. 6

FIG. 1 is a perspective view of a combined escutcheon, plate and hinged cover for a table top recessed switch device, showing my new design, with the hinged cover shown in the closed position;

FIG. 2 is an elevational view of one end thereof;

FIG. 3 is an elevational view of the opposite end thereof with the hinged cover shown in the open position;

FIG. 4 is a top plan view thereof with the hinged cover in closed position, the bottom of the escutcheon plate and hinged cover being substantially planar;

FIG. 5 is a front elevational view thereof; and

FIG. 6 is a rear elevational view thereof.

I claim:

The ornamental design for a combined escutcheon plate and hinged cover for a table top recessed switch device, substantially as shown and described.
